UNITED STATES PATENT OFFICE.

HARRY A. MCCLAIN, OF CANTON, OHIO.

DISH SCRAPER AND CLEANER.

Application filed February 12, 1926. Serial No. 87,803.

The invention relates to implements for cleaning food refuse from table kitchen ware and more particularly to a scraper or squeegee comprising a rubber scraper pad or 5 blade attached to a metal handle.

The objects of the improvement are to provide a device of the character referred to which will quickly and efficiently scrape grease or food from dishes and the like before the dishes are placed in the dishwater for washing; the device comprising a metal handle and side plate between which is clamped a sheet rubber pad or scraping blade, the device being so constructed that 10 it may be placed in the dishwater for thoroughly cleansing the same without danger of deteriorating the material of which it is formed.

An embodiment of the invention is illustrated in the accompanying drawing, in which—

Figure 1 is a perspective view of a dish scraper and cleaner embodying the invention;

Fig. 2, a plan view of the blank from which the handle is formed;

Fig. 3, a view similar to Figure 1 showing the handle and side plates formed of separate pieces, and

Fig. 4, a section on the line 4—4, Fig. 3.

Similar numerals refer to similar parts through the drawing.

The device includes a flexible sheet rubber scraper pad or blade 1 having the flat 35 lower scraping edge 2 and arranged to be clamped between the metal side plates 3 which may be formed integral with the handle 4 as shown in Figures 1 and 2 or separate from the handle 4^a as shown in 40 Figs. 3 and 4. With this latter construction a more economic use of the sheet metal from which the side plates and handles are formed, is possible.

In the form of the invention shown in 45 Figures 1 and 2, the side plates 3 are stamped from the same sheet of metal as the handle 4, being formed at opposite ends of the handle which is then bent upon itself, at its center, as shown in Figure 1.

To further strengthen the handle the portions of the same between the central bend or loop 5 and each side plate, may be substantially half-round in cross section forming a longitudinal strengthening rib as 55 shown at 6, the loop 5 forming an eye by

means of which the handle may be hung up on a hook or nail when not in use.

One of the side plates shown in Figures 1 and 2 is provided with preferably three tangs 7 stamped from same and arranged to be passed through the rubber pad and through registering apertures 8 in the other side plate and clinched thereon as shown in Figure 1, thus firmly and rigidly clamping the rubber pad or scraper blade 65 between the side plates.

As shown in Figs. 3 and 4, two tangs 7^a may be formed upon one of the side plates and passed through the rubber pad and apertures 8^a in the other side plate while 70 similar tangs 7^b may be provided upon one end of the handle 4^a and passed through the rubber pad and registering apertures in the side plates and through apertures 8^b in the other end portion of the handle and then 75 clinched as shown in Figs 3 and 4.

The side edges of the rubber pad or scraper blade are rounded as shown at 9 in order to fit the curved interiors of different dishes and pans while the corners 10 are provided 80 for entering into grooves, interstices and ornamental surfaces.

By means of this device practically all of the grease and food refuse may be easily and quickly scraped from dishes before they are placed in the dish water, without danger 85 of damaging the dishes, and the scraper itself may be placed in the dishwater and washed without hurting the material of which it is formed.

I claim:

1. A dish scraper and cleaner including a flexible pad, side plates of less area than the pad and clamping the pad on both sides, tangs upon one side plate extending through 95 the pad and other side plate and locked to the other plate and a handle fixed to the side plates.

2. A dish scraper and cleaner including a flexible pad, side plates of less area than the pad and clamping the pad on both sides, tangs upon one side plate extending through the pad and other side plate and locked to the other plate and a handle formed integral with the side plates.

3. A dish scraper and cleaner including a flexible pad, side plates of less area than the pad and clamping the pad on both sides, tangs upon one side plate extending through the pad and other side plate and locked to 110

the other plate and a handle formed of a strip of sheet metal bent upon itself at its center and fixed to the side plates.

4. A dish scraper and cleaner including a flexible pad, side plates of less area than the pad and clamping the pad on both sides, and a handle formed of a strip of sheet metal bent upon itself at its center and fixed to the side plates.

10 5. A dish scraper and cleaner including a

flexible pad, side plates of less area than the pad and clamping the pad on both sides, and a handle formed of a strip of sheet metal bent upon itself at its center and having a longitudinal strengthening rib formed therein and fixed to the side plates.

In testimony that I claim the above, I have hereunto subscribed my name.

HARRY A. McCLAIN.
